DESIGN FOR A HAT

Helen Barty, Brooklyn, N. Y.

Application May 17, 1939, Serial No. 85,041

Term of patent 3½ years

To all whom it may concern:

Be it known that I, Helen Barty, a citizen of the United States and a resident of the city of New York, in the county of Kings, Borough of Brooklyn, and State of New York, have invented a new, original, and ornamental Design for a Hat, of which the following is a specification, reference being had to the accompanying drawing, forming part thereof.

Fig. 1 shows the hat in perspective, as seen from one side thereof.

Fig. 2 is a similar view, as seen from the other side.

Fig. 3 is a similar view, as seen from in front of the hat, looking downward.

Fig. 4 is a bottom view of the hat.

Fig. 5 shows the pattern of the hat.

I claim:

The ornamental design for a hat, substantially as shown.

HELEN BARTY.
